DRY SHAVING DEVICE

Harry Landsiedel, Wilton, Conn., assignor, by
mesne assignments, to General Shaver Cor-
poration, Bridgeport, Conn., a corporation of
Delaware

Application March 4, 1937, Serial No. 128,936

4 Claims. (Cl. 30—43)

This invention relates to improvements in shaving devices of the type which do not necessitate the use of shaving preparations of any kind.

The general object of the invention is to provide an improved form of cutter head comprising an outer shear plate, and an inner cutter, movable transversely with respect thereto, and involving more particularly improvements in the cutter bar portions of the outer shear plate.

10 The more detailed objects of the invention will be apparent from the following description.

This invention resides substantially in the combination, construction, arrangement and relative location of parts, all as will be described in connection with the attached drawing.

The subject matter of this application is related to that of my copending application Serial No. 123,162, filed January 30, 1937 for Shaver.

In the accompanying drawing,
20 Figure 1 is a part of a side elevational view of the cutter head with many parts broken away to show other parts in cross section;

Fig. 2 is a vertical transverse sectional view through the cutter head;

25 Fig. 3 is an enlarged detail side elevational view of a portion of the cutter head.

In dry shaving devices of the type herein disclosed the outer shear plate, which is commonly slotted to provide a plurality of cutter bars, is applied at its outer face to the surface of the skin, and the inner cutter which operates in back of the shear plate against the rear face of the cutter bars therein. The hairs to be clipped enter the slots and are cut off at the rear edges of the cutter bars of the outer shear plate. It is at once apparent, therefore, that the thickness of the outer shear plate at the cutter bars, in part, at least, determines how close the hairs are cut off to the surface of the skin. The cutter bars are therefore of necessity made extremely thin with the result that they are physically weakened. The central object of this invention is to provide an improved construction at the cutter bars of the outer shear plate where portions of the active 40 lengths thereof are made much thinner without rendering them impractical.

Referring to the drawing at 1 is shown the upper end of the usual handle casing which houses the motor for operating the device. As 50 shown, the upper end of the casing is grooved as indicated at 2 to receive the cutter head assembly. The cutter head assembly is locked in the groove by a set screw not shown, and positioned therein by a pin 3 mounted in the casing 55 so as to engage a recess in the cutter head.

The cutter head comprises an outer member 4 which may be made from a solid block of suitable steel, or formed up in other ways, as is known in the art, to provide a hollow upper section having a relatively thin, substantially semicircular wall 6. This wall is provided with a series of transverse slots 7 extending therethrough and outwardly away from a central portion 8 which forms a continuous band extending longitudinally along the upper face of the wall 6. Aligned with the slots 7, and extending further down the sides of the wall 6, are a series of wider slots 9. These sets of aligned slots 7 and 9, on opposite sides of the wall 6, as is clear from Fig. 2, form the cutter bars 10 at the active portion which forms 10 what is commonly termed the outer shear plate. At this point it is apparent that the wall 6 is, at the portions under consideration, of substantially uniform thickness. In order to produce the finished shear plate it is now subjected to a series 20 of grinding operations to reduce the thickness of the bars 10 and the strip 8, leaving the raised ends as is clear in the figures. To accomplish this the ends of the bars 10 adjacent the strip 8 are ground on flat planes 11 which lie at an angle 25 of approximately 12 degrees to the horizontal. This would leave the strip 8 triangular in cross section but the top is preferably ground off to the form shown in Fig. 2 where it is more nearly rectangular in cross section and substantially of 30 uniform thickness. The bars 10 at their outer ends are again ground along flat planes 12 which lie at an angle of approximately 24 degrees to the horizontal. The result is that the bars 10, viewed 35 from the side as they are in Fig. 2, take a form as clearly illustrated where it comprises two parts each thinnest intermediate the ends of the parts as indicated at 13 and of increasing cross section away from the center towards the ends of the parts. This provides a relatively strong cutter 40 bar 10 which at no point is much thinner than four or five one-thousandths of an inch, and which, at the thinnest point, may be made less than two one-thousandths of an inch thick. The present commercial practice is to make the cutter 45 bars of the order of four one-thousandths of an inch thick. Any attempts to make a bar of uniform thickness any thinner than this, are met with practical difficulty. However, by means of the construction here disclosed, portions at least 50 of the cutter bars, in the case illustrated there are two such portions, may be made much thinner than this in shearing a very close shave. By reason of the fact that each bar is provided with two extremely thin portions, the device shaves 55

very rapidly, and since these portions lie so to speak in different planes, the outer shear plate does not have to be held against the skin as accurately as is true with the usual flat surface shaver. The slots 7 are provided with the wider portions 10 to permit easy entry of the hair thereinto by means of which they are guided to and into the narrow slots 7 where they may be cut. In practice it is desirable to make the slot 7 about 10 eight one-thousandths of an inch wide and the slots 9, from fifteen to twenty-five one-thousandths of an inch wide.

The inner cutter 14 is substantially circular in cross section and is provided with a series of 15 transverse slots 16 on the thinner wall formed by its eccentric bore to form the inner continuous cutter bars 15. As will be seen from Fig. 2, the length of the cutter bars 15 is sufficient to bridge the expanse of the cutter bars 10. 20 One end of the inner cutter is slotted as indicated at 17 to cooperate with the head 18 of the pin mounted in the member 4 to insure rectilinear reciprocation of the inner cutter. The sides of the inner cutter near the ends of the 25 slots 16 may be ground away as indicated at 19 to give relief and reduce the frictional resistance to movement of the inner cutter.

As is common in this art the inner cutter is engaged by an oscillatable lever 20 operated by 30 the motor not shown. At 21 are indicated a pair of pins which are resiliently urged by springs not shown in a direction to force the inner cutter against the rear faces of the cutters bars 10.

35 From the above description it will be apparent to those skilled in the art that some variation in the details of construction may be effected without departure from the true scope of the invention. I do not, therefore, desire to 40 be strictly limited to the disclosure as given for purpose of illustration, but rather to the appended claims.

What I seek to secure by United States Letters Patent is:

45 1. A dry shaving head comprising an outer shear plate slotted to form a series of cutter bars, each of the slots being continuous and comprising two portions of uniformly different

width and an inner cutter mounted for reciprocal movement across the rear faces of the cutter bars, said cutter bars being curved on their rear faces and having a plurality of flat intersecting outer faces.

2. A shaving device as described comprising an outer shear plate having a plurality of slots therein, the individual slots each having a wide and a narrow portion, and an inner cutter mounted for reciprocation transversely of the 10 rear faces of the cutter bars formed by said slots, said cutter bars increasing in thickness in both directions from two spaced points intermediate the ends thereof.

3. In a cutter head for a shaving implement 15 an outer shear plate comprising a curved wall having a plurality of parallel slots to form a plurality of cutter bars, the outer faces of the cutter bars forming two planes each lying at an acute angle to a common plane, and said 20 slots each comprising two portions of uniform but different width.

4. A shaver head of the type described comprising an outer member having a passage therethrough forming a wall, the rear surface of which 25 is a portion of a cylinder, the smallest dimension transversely of the axis of said passage being at least twice as great as the radius of said cylindrical portion, an inner reciprocable member mounted in said passage having a portion 30 of its outer surface cylindrical and engaging the cylindrical portion of the outer member, said inner member having a passage therethrough and being transversely slotted to form cutter bars, the outer member being provided 35 with slots which intersect its cylindrical portion and arranged in two rows, the slots of the respective rows terminating short of each other to form a reinforcing bar extending at right angles to the slots thereby forming two rows of 40 cutter bars, the outer faces of each row of cutter bars being cut away on two flat planes, the corresponding planes of each pair converging and forming acute angles with planes at right angles to the radial plane which includes their 45 lines of convergence respectively.

HARRY LANDSIEDEL.
